UNITED STATES PATENT OFFICE

148,540

DESIGN FOR A CONCRETE MIXER

Louis G. Hilkemeier, West Allis, Wis., and Oscar R. Knab, Cassopolis, Mich., assignors to Chain Belt Company, Milwaukee, Wis., a corporation of Wisconsin

Application April 3, 1946, Serial No. 128,220

Term of patent 14 years

(Cl. D14—3)

To all whom it may concern:

Be it known, that we, Louis G. Hilkemeier and Oscar R. Knab, citizens of the United States of America, residing respectively at West Allis, county of Milwaukee, State of Wisconsin, and at Cassopolis, county of Cass, State of Michigan, have invented a new, original, and ornamental Design for Concrete Mixer, of which the following is a specification, reference being had to the accompanying drawings, forming part thereof.

In the said drawings:

Fig. 1 is a side elevation of a concrete mixer showing our new design;

Fig. 2 is a rear elevation of the design shown by Fig. 1;

Fig. 3 is a perspective view of the design;

Fig. 4 is a plan view of the design.

The dotted line showing in Figs. 1 and 2 of the drawing is for illustrative purposes only.

We claim:

The ornamental design for a concrete mixer, substantially as shown and described.

LOUIS G. HILKEMEIER.
OSCAR R. KNAB.
